BRUSH ELEMENT WITH FIBERS HELD IN CHANNEL MEMBER AND METHOD OF MAKING SAME

William A. Parry, Manchester, Conn., assignor to
The Fuller Brush Company, Hartford, Conn.,
a corporation of Connecticut

Application November 29, 1949, Serial No. 129,905

16 Claims. (Cl. 15—199)

1

The invention relates to a brush element comprising a channel member with fibers held therein and projecting therefrom. The invention further relates to a method of making a brush element of the type mentioned.

Brush elements of the general character referred to are very well known, the fibers ordinarily being folded within the channel of the channel member and being engaged within the said channel by a longitudinally extending core wire which locks the folded fibers in place. Brush elements of the described conventional character are subject to the objection that, under some conditions of use, there is a tendency for the folded fibers to shift longitudinally within the channel and along the core wire, thus losing the desired uniformity of distribution and reducing the effectiveness of the brush element.

One object of the present invention is to provide a brush element of the general character described, wherein the folded fibers, instead of being held by a continuous longitudinal wire, are held by a longitudinal series of separate short fiber holding devices, such as staples, which are connected with the rear wall of the channel member. The short fiber holding devices or staples respectively engage separate groups or bunches of fibers, each group or bunch being firmly held and being positively prevented from any longitudinal movement along the channel member.

A further object of the invention is to provide a method of making a brush element having the features set forth in the preceding paragraph.

The drawings show in detail two alternative embodiments of the mechanical features of the invention and show the method of the invention, but it will be understood that the drawings are intended for illustrative purposes only and are not to be construed as defining or limiting the scope of the invention, the claims forming a part of this specification being depended upon for that purpose.

Of the drawings:

Fig. 1 is a fragmentary side view of a brush element embodying the invention with a portion shown in section, this view showing the brush element at an intermediate state of manufacture and illustrating certain steps of the method of manufacture.

Fig. 2 is a transverse sectional view taken along the line 2—2 of Fig. 1.

Fig. 3 is a view similar to Fig. 2 but showing the brush element in its completed form.

2

Fig. 4 is a rear view of the brush element in completed form as shown in Fig. 3.

Fig. 5 is a view similar to Fig. 3 but illustrating an alternative detail of construction.

Fig. 6 is a side view on a reduced scale showing an alternative brush element embodying the invention.

Fig. 7 is a fragmentary side view of the brush element shown in Fig. 6 with a portion thereof shown in section.

Fig. 8 is a sectional view taken along the line 8—8 of Fig. 6.

Fig. 9 is a sectional view taken along the line 9—9 of Fig. 7 but showing the brush element at an intermediate stage of manufacture.

Referring to the drawings, particularly Figs. 1 to 4 thereof, 10 represents a thin walled metallic channel member having a rear wall 12 and having two oppositely disposed side walls 14, 14, which are preferably similar. As shown, the channel member 10 is straight, but it is not necessarily straight as will presently appear. As more clearly shown in Fig. 2, the side walls 14, 14 are initially in widely diverging relationship with the rear wall 12.

Fibers are distributed along the channel member with their rear portions folded within the channel of the said member near the rear wall thereof. The fibers are preferably arranged in a longitudinal series of folded bunches, these bunches being preferably folded transversely as indicated at 16, 16. The fibers of the said bunches project forwardly from the said channel member 10. The successive bunches of fibers of the series are preferably closely adjacent, as shown, but the invention is not necessarily so limited. When the bunches of fibers are positioned as shown, some of the fibers of each bunch engage those of the next adjacent bunch and the several bunches of fibers thus cooperate with each other for holding the forward portions of the fibers substantially perpendicular to the rear wall of the channel member. The term "fibers" is herein used in a generic sense and is intended to include vegetable fibers, or bristles, or other animal fibers, or synthetic fibers, or metallic wires, or any other suitable filaments or brush material.

Means is provided for engaging the rear folded portions of the fibers to prevent forward and longitudinal movements thereof, this means including a longitudinal series of similar wire staples 18, 18. When the fibers are arranged in bunches and when the fibers of the said bunches are folded transversely as shown, the staples 18,

18 are disposed longitudinally. When the staples are disposed longitudinally they are preferably so positioned that the spaces between them are substantially less than the lengths thereof.

During manufacture the central portions of successive bunches of fibers are moved rearwardly into the channel of the channel member, the bunches of fibers being thus partly folded as shown in Fig. 2. Preferably and as shown, the bunches of fibers are engaged by the staples 18, 18, before the bunches of fibers are folded, such engagement being shown at the right in Fig. 1, the fibers in the said bunches being initially straight or substantially so. After each staple is engaged with a bunch of fibers, it is pushed rearwardly so that the rear portions of its prongs move through individual holes in the wall 12, the staple serving during its rearward movement to effect the before-mentioned partial folding of the fibers as shown in Fig. 2. The rear end portions of the prongs of each staple are bent at the rear to engage the rear face of the wall 12 as shown at 20, 20, the staple and the fibers of the corresponding bunch being thus locked in place. The rear end portions of the prongs of the staples are bent as described by engagement with a suitable anvil, not shown. The wall 12 of the channel member may be provided with preformed holes 22, 22 for receiving the prongs of the staples, but in some instances the prongs of the staples may be forced through the wall without the provision of any preformed holes.

With the parts in the intermediate stage of manufacture as shown in Figs. 1 and 2, the bunches of fibers 16, 16 have their folded portions at least partly within the channel of the channel member, the end portions of the fibers being in widely diverging relationship. The staples embrace the folded portions of the respective bunches of fibers and serve to hold the said bunches in place.

After the bunches of fibers have been engaged by the staples and after the staples have been locked in place in the channel member, the channel member is bent to move the walls 14, 14 toward each other from the relative positions shown in Fig. 2 to the relative positions shown in Fig. 3. The said movement of the side walls 12, 12 toward each other serves to complete the folding of the fibers. The bending of the channel member may be effected in any suitable manner, as for instance by a pressing operation, or by passing the channel member longitudinally between two opposed forming rolls. After the channel member has been bent as described, the walls 14, 14 converge forwardly to form a relatively narrow bite through which the fibers extend. At the said bite the walls 14, 14 grip the bunches of fibers to hold the forward portions thereof in approximate parallelism and in positions approximately perpendicular to the rear wall 12. The staples 18, 18 are so related to the side walls 14, 14 that the forward fiber holding portions of the staples are spaced rearwardly to a substantial extent from the forward edges of the channel side walls 14, 14. This relationship enables the forward edge portions of the channel side walls at the said bite to hold the fibers in the before-mentioned substantially parallel forward extending positions. The staples 18, 18 not only prevent forward movement of the bunches of fibers but also prevent longitudinal movement thereof along the channel member.

Preferably, the rear wall 12 of the channel member is formed with a forwardly projecting

longitudinal bead 24 which provides a longitudinal recess 26 at the rear. The bent rear end portions 20, 20 of the prongs of the staples 18, 18 are located entirely within the said longitudinal recess 26. Thus the said bent portions 20, 20 of the prongs do not project rearwardly beyond the lateral portions of the rear walls 12. When the brush element is mounted on a holder such as that indicated by the line 28 in Fig. 3, the lateral portions of the rear wall 12 can directly engage the holder without any interference with such engagement being offered by the bent prong portions 20, 20.

Fig. 5 shows a construction very similar to that shown in Fig. 3, differing, however, in that there is a bead 30 having relatively sharp corners instead of having rounded corners as does the bead 24 shown in Fig. 3. The longitudinal rear recess provided by the bead 28 has a flat face for engagement by the bent rear end portions of the prongs of the staples.

The brush element shown in Figs. 6 to 9 is generally similar to that shown in Figs. 1 to 5 except that the channel member instead of being straight is a completely closed ring 32. The channel ring 32 has an inner or rear wall 34 and has oppositely disposed side walls 36, 36. As shown in Fig. 9, the side walls 36, 36 are initially in widely diverging relationship with the rear wall 34.

A circumferential series of folded bunches of fibers is provided, the bunches of fibers being preferably folded transversely as indicated at 38, 38 and being similar to the bunches 16, 16. The successive bunches of fibers of the series are preferably closely adjacent as shown, but the invention is not necessarily so limited. The bunches of fibers 38, 38 are held by a circumferential series of staples 40, 40 similar to the staples 18, 18. The bunches of fibers and the staples are assembled with the channel ring 32 in the same manner as already described in connection with Figs. 1 to 4 and repetition of the description is unnecessary.

After the parts have been initially assembled as shown in Fig. 9, the channel ring is bent to move the walls 36, 36 toward each other from the relative positions shown in Fig. 9 to the relative positions shown in Fig. 8. The said bending of the channel ring may be effected in the manner previously described, the results being the same as previously described.

The inner or rear wall 34 of the channel ring 32 is formed with an outwardly or forwardly projecting annular bead 42 similar to the bead 24, the said bead 42 providing an annular recess 44 at the inner or rear face of the said wall. The bent inner or rear end portions 46, 46 of the prongs of the staples 40, 40 are located entirely within the said annular recess 44. Thus the lateral portions of the inner or rear wall 34 can directly engage a drum on which the brush element may be mounted without any interference with such engagement by the bent portions 46, 46 of the prongs of the staples.

What is claimed is:

1. In a brush element, the combination of a thin walled metallic channel member having a rear wall and having two oppositely disposed side walls which converge forwardly to form a relatively narrow bite near the front, bunches of fibers longitudinally distributed along the channel member with their rear portions folded transversely within the channel of the said member adjacent the rear wall thereof, the fibers of the

said bunches extending through and being gripped at the bite between the channel member side walls and projecting forwardly from the said channel member, and means engaging the rear folded portions of the said bunches of fibers to prevent forward and longitudinal movements thereof which means includes a longitudinal series of staples with the prongs of each staple extending rearwardly through individual holes in the rear wall of the channel member and bent to engage the rear face thereof.

2. In a brush element, the combination of a thin walled metallic channel member having a rear wall and having two oppositely disposed side walls which converge forwardly to form a relatively narrow bite near the front, a longitudinal series of bunches of fibers having their rear portions folded within the channel of the channel member adjacent the rear wall thereof and having their forward portions projecting forwardly from the said member, the fibers of the said bunches extending through and being gripped at the bite between the channel member side walls, and a longitudinal series of staples respectively embracing the rear folded portions of the fibers of the said bunches with the prongs of each staple extending rearwardly through individual holes in the rear wall of the channel member and bent to engage the rear face thereof.

3. In a brush element, the combination of a thin walled metallic channel member having a rear wall and having two oppositely disposed side walls which converge forwardly to form a relatively narrow bite near the front, a longitudinal series of bunches of fibers having their rear portions folded transversely within the channel of the channel member adjacent the rear wall thereof and having their forward portions projecting forwardly from the said member, the fibers of the said bunches extending through and being gripped at the bite between the channel member side walls and some of the fibers of each two adjacent bunches being in engagement with each other, and a longitudinal series of longitudinally disposed staples respectively embracing the rear folded portions of the fibers of the said bunches with the prongs of each staple extending rearwardly through individual holes in the rear wall of the channel member and bent to engage the rear face thereof.

4. In a brush element, the combination of a thin walled metallic channel member having a rear wall and having two oppositely disposed side walls which converge forwardly to form a relatively narrow bite near the front, a longitudinal series of bunches of fibers having their rear portions folded transversely within the channel of the channel member adjacent the rear wall thereof and having their forward portions projecting forwardly from the said member, the fibers of the said bunches extending through and being gripped at the bite between the channel member side walls, and a longitudinal series of longitudinally disposed staples respectively embracing the rear folded portions of the fibers of the said bunches with the prongs of each staple extending rearwardly through individual holes in the rear wall of the channel member and bent to engage the rear face thereof.

5. In a brush element, the combination of a thin walled metallic channel member having a rear wall and having two oppositely disposed side walls which converge forwardly to form a relatively narrow bite near the front, a longitudinal series of closely adjacent bunches of

fibers having their rear portions folded transversely within the channel of the channel member adjacent the rear wall thereof and having their forward portions projecting forwardly from the said member, the fibers of the said bunches extending through and being gripped at the bite between the channel member side walls, and a longitudinal series of longitudinally disposed staples respectively embracing the rear folded portions of the fibers of the said bunches with the prongs of each staple extending rearwardly through individual holes in the rear wall of the channel member and bent to engage the rear face thereof, the said staples being positioned with spaces between them which are substantially less than the lengths thereof.

6. In a brush element, the combination of a thin walled metallic channel member having a rear wall and having two oppositely disposed side walls which converge forwardly to form a relatively narrow bite near the front, a longitudinal series of bunches of fibers having their rear portions folded transversely within the channel of the channel member adjacent the rear wall thereof and having their forward portions projecting forwardly from the said member, the fibers of the said bunches extending through and being gripped at the bite between the channel member side walls, and a longitudinal series of longitudinally disposed staples respectively embracing the rear folded portions of the fibers of the said bunches with the prongs of each staple extending rearwardly through individual holes in the rear wall of the channel member and bent to engage the rear face thereof, the forward portions of the said staples being spaced rearwardly to a substantial extent from the said bite between the channel member side walls.

7. In a brush element, the combination of a thin walled metallic channel member having a rear wall and two oppositely disposed side walls, the said rear wall of the channel member being formed with a forwardly projecting longitudinal bead therein which provides a longitudinal recess at the rear, a longitudinal series of transversely folded bunches of fibers having their folded portions within the channel of the channel member, the said bunches of fibers being laterally engaged by the forward portions of the channel side walls and being thereby held in folded positions with the forward portions of the fibers substantially perpendicular to the rear wall of the channel member, and a longitudinal series of staples embracing the inner folded portions of the respective bunches of fibers with the prongs of the staples extending through individual holes in the bead in the rear wall of the channel member, the forward portions of the said staples being spaced rearwardly to a substantial extent from the said forward portions of the channel side walls and the prongs of the said staples having their rear portions located entirely within the said longitudinal recess formed by the said bead of the rear wall.

8. In an annular brush element, the combination of a thin walled metallic ring channel-shaped in cross section and having an inner or rear wall and also having two oppositely disposed side walls which converge outwardly or forwardly to form a relatively narrow bite near the outer front portion, bunches of fibers circumferentially distributed along the channel ring with their inner or rear portions folded transversely within the channel of the said ring

adjacent the inner or rear wall thereof, the fibers of the said bunches extending through and being gripped at the bite between the channel ring side walls and projecting outwardly or forwardly from the said channel ring, and means engaging the inner or rear folded portions of the said bunches of fibers to prevent outward or forward and circumferential movements thereof which means includes a circumferential series of staples with the prongs of each staple extending inwardly or rearwardly through individual holes in the inner or rear wall of the channel ring and bent to engage the inner or rear face thereof.

9. In an annular brush element, the combination of a thin walled metallic ring channel-shaped in cross section and having a rear wall and also having two oppositely disposed side walls which converge outwardly or forwardly to form a relatively narrow bite near the outer front portion, a circumferential series of bunches of fibers having their inner or rear portions folded within the channel of the channel ring adjacent the inner or rear wall thereof and having their outer or forward portions projecting outwardly or forwardly from the said ring, the fibers of the said bunches extending through and being gripped at the bite between the channel ring side walls, and a circumferential series of staples respectively embracing the inner or rear folded portions of the fibers of the said bunches with the prongs of each staple extending inwardly or rearwardly through individual holes in the inner or rear wall of the channel member and bent to engage the inner or rear face thereof.

10. In an annular brush element, the combination of a thin walled metallic ring channel-shaped in cross section and having a rear wall and also having two oppositely disposed side walls which converge outwardly or forwardly to form a relatively narrow bite near the outer front portion, a circumferential series of bunches of fibers having their rear portions folded transversely within the channel of the channel ring adjacent the inner or rear wall thereof and having their outer or forward portions projecting outwardly or forwardly from the said ring, the fibers of the said bunches extending through and being gripped at the bite between the channel ring side walls, and a circumferential series of circumferentially disposed staples respectively embracing the inner or rear folded portions of the fibers of the said bunches with the prongs of each staple extending inwardly or rearwardly through individual holes in the inner or rear wall of the channel member and bent to engage the inner or rear face thereof.

11. In an annular brush element, the combination of a metallic ring channel-shaped in cross section and having an inner or rear wall and two oppositely disposed side walls, a circumferential series of transversely folded bunches of fibers having their folded portions within the channel of the ring, the said bunches of fibers being laterally engaged by the outer or forward portions of the channel side walls and being thereby held in folded positions with the outer or forward portions of the fibers substantially perpendicular to the inner or rear wall of the channel ring, and a circumferential series of staples embracing the inner folded portions of the respective bunches of fibers with the prongs of the staples extending through individual holes in the inner or rear wall of the channel ring and bent to engage the inner or rear face there-

of, the outer or forward portions of the said staples being spaced inwardly or rearwardly to a substantial extent from the said outer or forward portions of the channel side walls.

12. In an annular brush element, the combination of a metallic ring channel-shaped in cross section and having an inner rear wall and two oppositely disposed side walls, the said inner or rear wall of the channel ring being formed with a forward projecting annular bead therein which provides a circumferential recess at the rear, a circumferential series of transversely folded bunches of fibers having their folded portions within the channel of the ring, the said 15 bunches of fibers being laterally engaged by the forward portions of the channel side walls and being thereby held in folded positions with the outer or forward portions of the fibers substantially perpendicular to the inner or rear wall 20 of the channel ring, and a circumferential series of staples embracing the inner folded portions of the respective bunches of fibers with the prongs of the staples extending through the bead in the inner or rear wall of the channel member, the 25 forward portions of the said staples being spaced rearwardly to a substantial extent from the said forward portions of the channel side walls and the said prongs of the staples having their rear portions located entirely within the said circumferential recess formed by the said bead of the 30 inner or rear wall.

13. The method of making a brush element which comprises, providing a thin walled metallic channel member having a rear wall and two 35 oppositely disposed side walls initially in widely diverging relationship with the rear wall, providing a succession of bunches of transverse fibers, providing a succession of U-shaped staples, engaging successive staples with the central portions of successive bunches of fibers, moving the 40 said central portions of the successive bunches of fibers rearwardly into the channel of the channel member to partly fold the said bunches, moving the prongs of the said staples rearwardly through individual holes in the rear wall of the channel member at longitudinally spaced positions so that the front portions of the staples hold the bunches of the fibers, bending the rear 45 portions of the prongs of the staples into engagement with the rear face of the rear wall of the channel member so as to lock the staples and the partly folded bunches in place, and finally bending the channel member to move the side walls thereof toward each other so that the said 50 side walls serve to additionally fold the bunches of fibers and to firmly grip them.

14. The method of making a brush element which comprises, providing a thin walled metallic channel member having a rear wall and two oppositely disposed side walls initially in widely diverging relationship with the rear wall, providing a succession of bunches of transverse fibers, providing a succession of U-shaped staples, embracing the central portions of successive bunches of 55 fibers with successive staples, moving the staples rearwardly to partly fold the embraced bunches of fibers and to move the prongs of the staples through individual holes in the rear wall of the channel member at longitudinally spaced positions, bending the rear portions of the prongs of the staples into engagement with the rear face of the rear wall of the channel member so as to lock the staples and the partly folded bunches in place, and finally bending the channel member to move the said walls thereof toward each 60 65 70 75

other so that the said side walls serve to additionally fold the bunches of fibers and to firmly grip them.

15. The method of making a brush element which comprises, providing a metallic channel member having a rear wall and two oppositely disposed side walls initially in widely diverging relationship with the rear wall, the said rear wall of the channel member being formed with a forward projecting longitudinal bead therein which provides a longitudinal recess at the rear, providing a succession of bunches of transverse fibers, providing a succession of U-shaped staples, embracing the central portions of successive bunches of fibers with successive staples, moving the staples rearwardly to partly fold the embraced bunches of fibers and to move the prongs of the staples through individual holes in the bead of the rear wall of the channel member at longitudinally spaced positions, bending the rear portions of the prongs of the staples into engagement with the rear face of the rear wall of the channel member entirely within the longitudinal recess formed by the said bead of the rear wall so as to lock the staples and the partly folded bunches in place, and finally bending the channel member to move the side walls thereof toward each other so that the said side walls serve to additionally fold the bunches of fibers and to firmly grip them.

16. The method of making an annular brush

element which comprises, providing a metallic ring channel-shaped in cross section and having an inner or rear wall and two oppositely disposed side walls initially in widely diverging relationship with the inner or rear wall, providing a succession of bunches of transverse fibers, providing a succession of U-shaped staples, embracing the central portions of successive bunches of fibers with successive staples, moving the staples inward or rearward to partly fold the bunches of fibers and to move the prongs of the staples through individual holes in the rear wall of the channel member at circumferentially spaced positions, bending the inner or rear portions of the prongs of the staples into engagement with the inner or rear face of the inner or rear wall of the channel member to lock the staples and the partly folded bunches in place, and finally bending the channel ring to move the side walls thereof toward each other so that the said side walls serve to additionally fold the bunches of fibers and to firmly grip them.

WILLIAM A. PARRY.
